(57) **CLAIM**

The ornamental design for an automobile and/or toy replica thereof, as shown and described.

DESCRIPTION

FIG. 1 is a front perspective view of an automobile and/or toy replica thereof showing our new design;

FIG. 2 is a rear perspective view thereof;

FIG. 3 is a front elevational view thereof;

FIG. 4 is a rear elevational view thereof;

FIG. 5 is a top plan view thereof; and,

FIG. 6 is a right side elevational view thereof, the left side elevational view being a mirror image of FIG. 6.
